UNITED STATES PATENT OFFICE

155,264

DESIGN FOR A PHOTOGRAPHIC CAMERA

Jacques Bolsey, New York, N. Y.

Application June 14, 1948, Serial No. 146,939

Term of patent 14 years

(Cl. D61—1)

To all whom it may concern:

Be it known that I, Jacques Bolsey, a citizen of the United States of America, residing at New York, New York, have invented a new, original, and ornamental Design for Photographic Cameras, of which the following is a specification, reference being had to the accompany drawing, forming part thereof.

Fig. 1 is a front perspective view of a photographic camera, showing my new design;

Fig. 2 is a top view; and

Fig. 3 is a perspective rear view.

I claim:

The ornamental design for a photographic camera, as shown.

JACQUES BOLSEY.
